DEVICE FOR LOOSENING UP TOBACCO

Hübert Schlossmacher, Hamburg-Bergedorf, Germany, assignor to Kurt Körber & Co., K.-G., Hamburg-Bergedorf, Germany

Application June 8, 1955, Serial No. 514,053

Claims priority, application France June 9, 1954

4 Claims. (Cl. 131—109)

This invention relates to a device for loosening up tobacco in which the tobacco is discharged from a discharge device onto a slowly moving endless band, continuously removed from the end of said band and, if desired, conveyed further in order to deliver in a loosened up condition from conveyors, silos, mixing plants, or other similar transportation and storage devices tobacco that has been stored to great heights and that is thoroughly moistened, and to dose out said tobacco so that a treatment device associated with said transportation and storage device is supplied with a given amount of tobacco per unit of time.

It is known per se to deliver tobacco piled to great heights and thoroughly moistened to a further treatment device by means of suitable transportation devices such as slowly moving conveyor bands, in connection with such storing and moistening. However, until now it has been difficult to deliver the tobacco at the discharge end in sufficiently loosened condition and particularly in satisfactorily uniform quantities.

This work was originally done by hand by means of suitable discharge tools. However, it has been attempted to eliminate the resulting differences in discharge and looseness through suitable devices as, for example, by building in a rake band at the discharge end. Said embodiment turned out, however, not to fulfill the requirements for such an installation.

According to this invention, therefore, a device is used for the loosening up which is characterized by rotating rake wheels arranged in staggered position at the front end of the layers of tobacco. Said rake wheels are journaled in stationary bearing frames which may be adjustable in relation to each other. Furthermore, the arrangement can be such that a rake wheel disposed at a higher level may rotate at a higher speed than a lower wheel so that the tobacco is removed from the front wall in quantities that are not too great. The tobacco removed by the rake wheels is discharged into a swinging conveyor chute which moves the tobacco ahead or—in the case of a plurality of devices for loosening up the tobacco—the tobacco may be discharged onto a collector band.

The embodiment described below as an example of the invention relates particularly to a loosening and remover device in an elongated mixing machine for cut tobacco without, however, limiting the subject matter of the invention, specifically to such a machine. For illustration, reference is had to the diagrammatic views in the drawings, in which

Fig. 1 shows a longitudinal section of the device provided with a swinging transport chute,

Fig. 2 is an elevation in the direction of the arrow A of Fig. 1, with parts broken away,

Fig. 3 shows a swinging transport chute of different construction, and

Fig. 4 shows the chute of Fig. 3 viewed from the right-hand side of said figure.

2

In the only partially shown mixing machine, for example, cut tobacco 1 is mixed by known means on a conveyor 2 which moves slowly in the direction of the arrow 1'. In front of the discharge end for the tobacco 1, 5 three rake wheels 3, 4 and 5 are arranged in staggered relation and driven so that the wheel at the highest level rotates at a greater speed than the wheel therebelow. The rake wheels 3, 4 and 5 rotate in the direction in which the pins are bent and in substantially the same direction as shown in Patent 260,958, C. G. Emery, July 11, 1882. The pins which, for example, are arranged along a screw line on the wheels 3, 4 and 5 are provided with transverse plates 6 in order to prevent the tobacco from remaining hanging on the pins. The wheels, 3, 4 10 and 5 are mounted in bearings 7, 8 and 9, respectively, in a frame 10 and the wheels are adjustable therein. Below the frame a funnel 11 is disposed through which tobacco passes into a swinging transport chute 12 arranged therebelow. The bottom of said transport chute may be 15 horizontal or inclined. The swinging transport chute can be secured to the machine frame by means of blade or coil springs in a manner known per se. The oscillatory movement can be achieved by means of a crank drive in any known way and provided with a connecting rod 20 13 pivoted to the chute at the center of gravity thereof. The chute is guided by means of profile rolls 15 mounted between two brackets 14 on the chute and adapted to run on short rails 16. In order to further loosen up the tobacco, an additional rake device 17 may be disposed 25 in the chute 12 and said rake device 17 comprises vertically and horizontally adjustable rake pins 18 fixedly secured to a shaft. Said shaft is fixedly connected to the chute 12 in bearings 19 and the chute is given an oscillatory movement either transversely to the direction of 30 transportation in the mixing machine or in said same direction.

When a plurality of mixing machines with such rake wheels are arranged beside each other, the falling tobacco may move onto a common collector band (not shown) 40 from which the tobacco is conveyed to the treatment units mentioned above.

What I claim is:

1. In a device for loosening cut tobacco which is deposited in the form of a thick layer upon a slowly moving endless conveyor band and at one end of the latter is discharged into a funnel, a frame arranged at the discharge end of said conveyor band and above said funnel, a plurality of rake wheels rotatably supported in said frame in a downwardly stepped fashion above and in front of the discharge end of said conveyor band, the uppermost rake wheel being arranged to engage and loosen substantially the upper half of said tobacco layer as it reaches said discharge end, the next lower rake wheel being arranged to engage and loosen substantially the lower half of said tobacco layer as it reaches said discharge end, and another rake wheel being arranged in a still lower plane for receiving and loosening tobacco previously loosened by said two first mentioned rake wheels before said tobacco drops into said funnel.

2. In a device for loosening cut tobacco which is deposited in the form of a thick layer upon a slowly moving endless conveyor band and at one end of the latter is discharged into a funnel, a frame arranged at the discharge end of said conveyor band and above said funnel, a plurality of rake wheels rotatably supported in said frame in a downwardly stepped fashion above and in front of the discharge end of said conveyor band, the uppermost rake wheel being arranged to engage and loosen substantially the upper half of said tobacco layer as it reaches said discharge end, the next lower rake wheel being arranged to engage and loosen substantially the lower half of said tobacco layer as it reaches said discharge end.

charge end, and another rake wheel being arranged in a still lower plane for receiving and loosening tobacco previously loosened by said two first mentioned rake wheels before said tobacco drops into said funnel, all of said rake wheels having the same diameter.

3. In a device for loosening cut tobacco which is deposited in the form of a thick layer upon a slowly moving endless conveyor band and at one end of the latter is discharged into a funnel, a frame arranged at the discharge end of said conveyor band and above said funnel, a plurality of rake wheels rotatably supported in said frame in a downwardly stepped fashion above and in front of the discharge end of said conveyor band, the uppermost rake wheel being arranged to engage and loosen substantially the upper half of said tobacco layer as it reaches said discharge end, the next lower rake wheel being arranged to engage and loosen substantially the lower half of said tobacco layer as it reaches said discharge end, and another rake wheel being arranged in a still lower plane for receiving and loosening tobacco previously loosened by said two first mentioned rake wheels before said tobacco drops into said funnel, all of said rake wheels having the same diameter, and rotate in a direction in which they tend to lift the tobacco upwardly as it is removed from the charge end of the conveyor band.

4. In a device for loosening cut tobacco which is deposited in the form of a thick layer upon a slowly moving endless conveyor band and at one end of the latter is discharged into a funnel, a frame arranged at

the discharge end of said conveyor band and above said funnel a plurality of rake wheels rotatably supported in said frame in a downwardly stepped fashion above and in front of the discharge end of said conveyor band, the uppermost rake wheel being arranged to engage and loosen substantially the upper half of said tobacco layer as it reaches said discharge end, the next lower rake wheel being arranged to engage and loosen substantially the lower half of said tobacco layer as it reaches said discharge end, and another rake wheel being arranged in a still lower plane for receiving and loosening tobacco previously loosened by said two first mentioned rake wheels before said tobacco drops into said funnel, all of said rake wheels having the same diameter, and each higher positioned rake wheel being rotated at a greater speed than the next lower rake wheel.
